United States Patent Office.

R. N. ALLEN, OF PITTSFORD, VERMONT.

Letters Patent No. 72,583, dated December 24, 1867.

DRYING-APPARATUS.

The Schedule referred to in these Letters Patent and making part of the same.

TO ALL WHOM IT MAY CONCERN:

Be it known that I, R. N. ALLEN, of Pittsford, in the county of Rutland, and State of Vermont, have invented certain new and useful Improvements in a Drying-Apparatus; and I do hereby declare that the following is a full and complete description of the same, reference being had to the accompanying drawings, making a part of this specification, in which—

Figure 1 is a side view of the apparatus.

Figure 2 is a view of the top.

Figure 3, a view of the inside.

Figure 4 is a front view.

Like letters of reference refer to like parts in the views.

A, fig. 2, is a case or cylinder, from each head of which project pipe-journals B B', and upon which the cylinder is hung, and made to revolve between the sides or standards C. The pipe or journal B' connects with the heater D, by being fitted closely in the pipe E, projecting from the heater, and the journal B is fitted to the flue F, leading into the stack or chimney G. Within the case referred to, is arranged an annular chamber or cylinder, H, fig. 3, which, it will be seen, is considerably less in size than the outer one, A, leaving a wide space, I, between the two. The ends of the annular chamber are closed by tightly-fitting heads J. Placed at equal distances around the case A, are four rollers, K, over which, and around the cylinder, is an endless apron, L, the direction of which is shown in fig. 4, in which it will be seen that the apron covers the case or cylinder nearly its entire circumference.

The practical use of this apparatus is for drying paper or paper board, which, as ordinarily done, is a work attended with much trouble and great length of time, in consequence of the thickness of the paper, and more especially is this the case in damp and winter weather. By the use of this drier, this labor and time is very considerably lessened, by a more rapid drying and less handling of the paper, and which is done in the following manner: The heater D is heated up by the furnace M, the heat from which, on passing into the case, through the pipe and journal E and B', is deflected by the head J of the annular chamber, and thereby caused to flow over and around the chamber H to the inner surface of the case, thus heating the case more or less as the amount of heat generated in the furnace.

It will be obvious that, by the introduction of the chamber H, a much less volume of heat will be required to heat the case than if the chamber were not used, as the heat is necessarily thrown to the surface instead of passing directly through the case, as would be the fact in the absence of the chamber. The case is made to revolve by any appropriate mechanical appliances, and, as it does so, the sheets of paper, which are first partially dried, are placed on the apron, which carries them around, bringing them in contact with and pressing against the heated surface of the case, which, on being carried around slowly, according to the temperature of the case, or the degree of dampness of the paper, is soon dried and delivered, at the opposite side from which it was fed, to the drier. By this means the paper is easily and quickly dried, with much less labor and time than in the ordinary way. It is also much smoother and free of wrinkles.

By the use of this apparatus, paper board can be made as rapidly in winter as in the warmer seasons, for, in cold, wet weather, it has been found almost impossible to thoroughly dry the paper, only in highly-heated rooms, which is attended by great expense and labor.

What I claim as my improvement, and desire to secure by Letters Patent, is—

1. The cylinder A, with an annular chamber revolving upon tubular journals so arranged that the said journals and annular chamber shall form an avenue for the passage of waste heat from the flue of the fireplace to the chimney, and at the same time utilize said heat in its transit, substantially as and for the purpose set forth.
2. The revolving cylinder A, having an interior chamber H and hollow journals B B', in combination with the flue of the boiler and stack, arranged and operating for the purpose, substantially as set forth.
3. The apron L, rollers K, in combination with the cylinder A, arranged to receive the waste heat through one journal and discharge the same through the other into the chimney or stack, substantially as and for the purpose set forth.

R. N. ALLEN.
